MATTRESS COVER AND THE LIKE

Alvin D. London, Baltimore, Md., assignor to
Al-lon Manufacturing Company, Inc., Baltimore, Md., a corporation of Maryland

Application October 24, 1939, Serial No. 301,055

4 Claims. (Cl. 5—354)

This invention relates to slip covers and more particularly to slip covers for mattresses, cushions and the like for preserving the appearance thereof and preventing same from becoming dirty or soiled.

5 While the improved cover of the present invention is capable of use with cushions or the like, it is particularly adapted for use with mattresses and is so shown in the single physical embodiment disclosed.

10 Slip covers for mattresses have been in use for some time, such covers generally being in the form of bags substantially of the length of the mattress, the cover having buttons, snap fasteners or similar spaced attaching elements for closing the open ends of the bags and maintaining same on the mattress.

15 While such a cover to a large extent prevented the mattress from becoming soiled or dusty, nevertheless its construction was such that dust or dirt entered through the closed ends of the cover for the reason that the securing means such as snap fasteners or the like were in substantial spaced relation, thus allowing gaps in the material of the cover through which dust could readily enter and permeate the mattress. In some instances the use of slideable fasteners known as zippers have been employed on mattress covers. However, very great lengths of these zippers were 20 necessary and this materially added to the expense of the cover. Furthermore, slideable fasteners, snap fasteners, buttons and the like are susceptible to injury during washing and in addition slip cover textiles have a tendency to shrink upon laundering thus destroying the effectiveness of the aforementioned closure means.

25 It is accordingly a primary object of this invention to provide a special closure on a slip cover for a mattress which will positively preclude the admission of dust or dirt to the interior thereof and still maintain the effectiveness of the closure means after laundering.

30 Furthermore covers as heretofore used were difficult to assemble due to the relatively great length of fabric from the open to the closed ends of the cover and it is a further aim of this invention to provide a slip cover for mattresses which can be quickly and easily installed in position; which is inexpensive to manufacture and effective in use.

35 Other objects and advantages will appear from the following detailed description of the invention hereinafter appearing when taken in connection with the accompanying drawings, where-

Fig. 1 is a perspective view of the improved cover in operative position on a mattress.

Fig. 2 is a similar view showing the cover partially in position on the mattress.

Fig. 3 is a top plan view of a mattress, showing only the improved cover in horizontal section in a plane represented by line 3—3 in Fig. 1.

Fig. 4 is a side view of the mattress showing the cover in longitudinal vertical section in a plane represented by line 4—4 in Fig. 1.

Referring to the drawings by reference characters, and wherein like characters designate like parts in the different views, M designates a mattress which may be of size for a single or a double bed or may in fact be of a size for a crib or a 15 pillow, the cover forming the subject matter of this invention being adapted for use with cushions or mattresses of any preferred dimensions.

The improved cover is represented in its entirety at 10 and may be constructed of any desired fabric material and comprises a rectangular bottom 11, a similar rectangle top 12, both formed of a single layer of material, and a further single layer of material 13 forming one end 14 and substantially one-half of each of the opposite sides 15 of the cover, as is clearly indicated in Figure 3 of the drawings.

The remaining portions of the opposite sides 15 and the remaining end 16 of the cover 10 are formed of double fabric layers 17 and 18, the layer 13 and the layers 17 and 18 being suitably stitched together at their adjacent ends at 19 on vertical lines which are preferably substantially centrally of the opposite ends 14 and 16 of the cover 10.

35 The lower and upper edges of the fabric layer 13 are stitched to the bottom and top layers 11 and 12 as indicated at 20 and 21 respectively, the lower edge of the layer 17 being stitched to the bottom layer 11 as indicated at 22 and the upper edge of the layer 18 being stitched to the top layer 12 as is indicated at 23. The upper edge of the layer 17 is provided with an elastic 24 which extends continuously from one stitched line 19 to the other and the lower edge of the layer 18 is 40 provided with a like elastic 25.

In Fig. 2 the cover is shown partially applied to the mattress M and before application to the mattress is begun the bottom and top layers 11 and 12 with their respective edge layers 17 and 18, are both rolled back to the position of layers 12 and 18 in Fig. 2 whereby a bag of substantially only one half the length of the mattress need be pulled over the end thereof which obviously can be done with greater facility than 45 50 55

when the bag is of the full length of the mattress as heretofore used or proposed.

When this half portion of the cover has been pulled over the corresponding portion of the mattress the bottom layer 11 and associated edge layer 17 are drawn forward to the position indicated in Fig. 2, the elastic 24 facilitating the pulling of the edge layer 17 over the bottom of the mattress and also holding the upper edge of the layer 17 into firm contact with the upper edge of the mattress.

The top layer 12 and corresponding edge layer 18 are finally drawn forward and the layer 18 pulled over the upper edge of the mattress to the position indicated in Fig. 1, the elastic 25 facilitating the pulling of layer 18 over the edge of the mattress as well as binding the lower edge thereof into firm contact with the layer 17.

With the improved closure construction described it will be seen that application of the cover to a mattress is greatly facilitated and by the provision of the elastics 24 and 25 dustproof joints are provided between the relatively movable fabric layers whereby the mattress is protected against soiling and secure against ingress of dust or dirt. Furthermore, laundering of the cover and shrinking of the material will not materially affect the fit of the cover.

Finally, in lieu of the elastics 24 and 25 other adjustable closure means may be employed. A good example of such means are draw or tie cords. These are particularly valuable when the material of the cover is subject to more than average shrinking or laundering. Obviously, other equivalent adjustable closure constructions may be advantageously used.

While I have described the invention in detail, yet this is to be considered illustrative only and not restrictive, the scope of the invention being defined in the subjoined claims.

What I claim and desire to secure by Letters Patent is:

1. A fabric cover for mattresses and the like comprising a rectangular bottom portion, a rectangular top portion, and an edge portion; the bottom and top portions each being of a single ply throughout its extent, the edge portion comprising a single ply secured to the margins of the bottom and top portions and extending around approximately one half of the cover, and a double ply extending around the other half of the cover with one edge of one ply secured to the margin of the bottom portion and the opposite edge of the other ply secured to the margin of the top portion, the other edges of the plys being free and the two plys overlapping in the applied position of the cover.

2. The structure defined in claim 1, in which the free edges of the overlapping plys are each provided with an elastic for maintaining firm engagement between the plys and with the edge of the mattress.

3. A closure for a mattress cover including top, bottom and edge portions; comprising a pair of overlapping fabric sections included in said edge portion and forming one end and substantial lengths of the opposed sides thereof, one fabric section having one edge thereof secured to the margin of the top portion, the other fabric section having the opposed edge thereof secured to the margin of the bottom portion, the opposed edges of the fabric sections being free and respectively positioned adjacent the bottom and top edges of a mattress in the applied position of the cover.

4. The structure defined in claim 3, wherein the free edges of the fabric sections are adjustable for firm engagement of the second section with the edge of a mattress and for firm engagement of the first section with the second section.

ALVIN D. LONDON.
